UNITED STATES PATENT OFFICE.

ADOLPH C. RECKER, OF OAKVILLE, CONNECTICUT, ASSIGNOR TO WATERBURY M'F'G CO., OF WATERBURY, CONNECTICUT, A CORPORATION.

FLASH-LIGHT CASE.

1,280,300.

Specification of Letters Patent.

Patented Oct. 1, 1918.

Application filed March 6, 1918. Serial No. 220,814.

To all whom it may concern:

Be it known that I, ADOLPH C. RECKER, a citizen of the United States, residing at Oakville, in the county of Litchfield and State 5 of Connecticut, have invented a new and useful Improvement in Flash-Light Cases; and I do hereby declare the following, when taken in connection with the accompanying drawings and the characters of reference 10 marked thereon, to be a full, clear, and exact description of the same, and which said drawings constitute part of this application, and represent, in—

Figure 1 a view in side elevation of my 15 improved flash-light case with its inner end partly in longitudinal central section.

Fig. 2 a plan view of the inner end of the case.

Fig. 3 a detached perspective view of the 20 receptacle-shell located within the removable cap applied to the inner end of the case.

Fig. 4 a broken view in central longitudinal section on an enlarged scale of the inner 25 end of the case.

My invention relates to an improved flash-light case, the object being to furnish the removable cap applied to the inner end of the case with a glazed receptacle for the 30 reception of some feature of utility or amusement, such as a game, a photograph, or a compass.

With these ends in view, my invention 35 consists in a flash-light case having a hollow body provided at its outer end with a lamp, and at its inner end with a removable cap containing a glazed receptacle.

My invention further consists in a flash-light case having certain details of construction 40 as will be hereinafter described and particularly recited in the claims.

In carrying out my invention as herein shown, I locate a shallow, circular receptacle-shell 2 within the removable screw-cap 45 3 provided for the inner end of the tubular body 4 of the case. The opposite end of the said body is furnished with a removable screw-cap 5 mounting an ordinary bull's-eye 6 and made removable for access to the ordinary tiny incandescent lamp which is not shown. The body 4 receives a removable cylindrical battery 7 normally held in con-

tact with the said lamp by means of a spiral battery-spring 8 the outer end of which rests upon the bottom of the receptacle-shell 55 2 aforesaid. The inner portion of the removable cap 3 is formed with rolled-in threads 9 adapted to engage with corresponding rolled-in threads 10 in the outer portion of a band or collar 11 fixed to the 60 inner end of the body 6. The outer end of the shell 2 is formed with an inwardly turned bearing-flange 12 while the cap 3 is formed with a similar inwardly turned flange 13, the glass 14 by means of which the 65 shell 2 is glazed being pinched between these two flanges.

As herein shown, the bottom of the receptacle-shell 2 is formed with five shallow hemispherical pockets 15 symmetrically arranged and designed to receive the same number of balls 16 confined in the receptacle by the glass 14. These depressions and balls constitute a game, the object of which is to simultaneously seat the several balls in the 75 several pockets 15, this achievement requiring patience and a steady hand. The "game" is played by holding the flash-light in a vertical position and rocking it ever so slightly on its vertical axis. 80

In place of this ball-game, a photograph might be located within the receptacle, or a compass or some other corresponding use of it might be made. It will be observed that the bottom of the receptacle forms a 85 support for the spring 8 which must be removed at the time the cap 3 is removed for the removal and replacement of the battery 7.

I claim:—

1. In a flash-light, the combination with a tubular body, of a removable cap for the inner end thereof, an independently formed receptacle-shell located within the said cap and having its inner end closed and its outer end open, and a glass closure interposed between the outer end of the cap and the said shell and serving to close the receptacle formed by the latter. 95

2. In a flash-light, the combination with the tubular body thereof, of a collar or band permanently applied to the inner end of the said body, a cap adapted to be removably secured to the said collar and having its 100

inner end turned inward to form a flange, a receptacle-shell located within the said cap and having its outer end turned inward to form a bearing-flange, and a piece of glass 5 interposed between the said flanges and serving to glaze the receptacle formed by the said shell.

In testimony whereof, I have signed this specification in the presence of two subscribing witnesses.

ADOLPH C. RECKER.
